UNITED STATES PATENT OFFICE

JANE C. GIFFORD, OF NEW YORK, N. Y.

BUST SUPPORTER

Application filed January 30, 1930. Serial No. 424,535.

My invention relates to wearing apparel and more particularly to a garment of the type of bathing suit having a self-contained means for supporting the bust portion of the 5 human figure.

In the prior art it has been found difficult to obtain a satisfactory support of the bust while preserving graceful appearance and freedom of movement. For this purpose it 10 has been customary to employ a separate garment of the well-known type of brassière, having a front piece, shoulder straps and band across the back connected to the shoulder straps. Such a type of garment by exerting 15 a circumscribing pressure around the figure of the wearer, compressed the bust, thus holding it back firmly. It has been found in practice that the effect created by this means of support is inartistic in that it 20 produces a rigid appearance and restrains the natural movement of the upper portion of the body, thus detracting from the effect of grace and ease essential to present day modes. The 25 fact that it constricts the chest and hampers the shoulder movements renders it unsuitable for wear in any athletic pursuit, more particularly swimming, and the compression exerted by it tends to break down and render flabby the muscular structure of the bust. 30 It has also been found in practice that the brassière is unsightly when worn with modern garments of the type of "sun-tan" bathing suit in which the back is substantially cut away. The back strap of the brassière, 35 which is an essential structural feature, is exposed to view and detracts from the harmony of line and modish appearance of the suit.

The primary object of this invention is to 40 provide a means of supporting the bust self-contained within an outer garment and employing as a principle of support the upward tension of the outer garment toward the shoulders rather than the constriction of the bust within a circumscribing band, and thus eliminating among others the disadvantages stated 45 above. Other objects and advantages of my invention will be apparent from the following description taken in conjunction with the accompanying drawing which forms a part of 50 this specification and in which

Figure 1 is a diagrammatic arrangement showing the manner in which my garment may be worn on a woman's form, the construction of the bust supporter, where concealed by the front piece, being indicated by 55 dotted lines.

Figure 2 is a rear elevation thereof, the interior construction of the bust supporter where concealed by the back piece being indicated by dotted lines. 60

Figure 3 is a cross section of Figure 2 taken at 3-3, and

Figure 4 is a detail view of the construction of the bust supporter. 65

Referring more particularly to the drawing in which like reference characters denote like parts, the body of the bathing suit or dress, which may be made up in any desired manner and of any desired material, is provided with a front portion 1 which is adapted to extend down toward the waist of the wearer and is adapted to be dropped below the arm pits. It also includes a back portion 2 adapted to fit the back of the wearer. At the top, the 70 front and back pieces are joined with the customary shoulder straps 4 as is well understood. 75

To prevent the bust portion of the garment from stretching or sagging and to support the bust of the wearer I provide a transverse strip 5 extending across the bust portion of the figure underneath the front piece of the garment, and fasten it in any suitable manner such as, for example, to the front piece 1 along the lower seam 6, the upper seam 9 and to the side seams of the garment between the front and back pieces adjacent the arm-holes. The material composing the transverse strip 5 is shaped in such a manner 80 that the upper edge 7 of the strip is longer than the lower edge 8. In referring to the edges 7 and 8 as "upper" and "lower" I have reference to their relation as viewed in the drawing. Moreover, the material is not laid flat along the seam 6, but is preferably gathered so that the transverse strip 5 toward its upper portion, may be sufficiently slack to adapt itself to the fullness of the bust of the wearer. The lower edge 8 of the transverse 85 strip is shaped in such a manner that it fol- 90

100

lows the outer curve of the bust of the wearer. The upper edge 7 of the transverse strip 5 is shaped or cut away in such a manner that it follows the curve of the bust close to the body. 5 It may be attached as shown in Figures 1 and 2 to the outer garment at a central portion along the seam 9. When the garment is worn the transverse strip 5 does not extend over the bust, but fits under or cups the breasts, 10 assuming the position particularly indicated in Figure 3. At the extremities of the seam 9 and at the points 12 and 12', the transverse strip is attached to elastic bands 10 and 10', and 11 and 11', these bands being attached to 15 the elastic bands 13 and 13', which are attached to the upper front portion of the shoulder strap of the garment. These elastic bands take up all of the slack portion of the transverse strip not required for adjustment 20 to the fullness of the bust, thus causing the strip to fit snugly around the lower portions of the breasts. The upward tension of the bands toward the shoulder causes the transverse strip 5 to exert an upward pull 25 against the lower portion of the breasts and thus affords support to the bust. In this manner the bust is upheld firmly by a natural reinforcement of the muscular structure thereof, while at the same time it is left free 30 and its natural structure is preserved and defined.

It is seen that this garment affords support without either rigidity or compression, thus enabling the wearer to present a graceful appearance and preserve perfect freedom of movement.

It is also seen, particularly with reference to Figure 2, that this means of bust support is particularly adapted for use in garments of 40 which the back is cut very low, as in the type of "sun-tan" bathing suit, and wherein the back strap of the brassière type of bust supporter would be exposed to view.

A further advantage of my invention is 45 that the wearer has in one unified garment the equivalent of two independent garments of the prior art. The combined garment may be put on or taken off with greater facility than the independent garments and requires 50 fewer adjustments and fastenings.

The invention is particularly advantageous in garments of the type of bathing suit, in that the bust supporter being combined with the suit, is not subject to separation or loss. My 55 invention is only shown in a garment of the type of bathing suit. It is obvious that there are possible modifications without departing from the spirit of my invention. For example it is applicable to underwear, evening dress, or any article of apparel in which it is desired to eliminate the unsightly brassière, and preserve the advantages described 60 above. For these reasons I do not wish to be limited by this description, but only by 65 the prior art and the appended claims.

I claim:

1. In combination with a woman's garment of the type that is cut low in the back so as to expose the central part of the back of the wearer, a bust supporter comprising a transverse piece of material extending across the inside of the front portion of the garment above the lower extremity of the cut low portion of the back and terminating at the sides of the garment, thereby leaving the central portion of the back of the wearer entirely exposed and avoiding a circumferential restriction around the bust of the wearer, said transverse piece of material being stitched to the front portion of the garment along 70 one edge and having portions of the opposite edge free to fit under the breasts of the wearer, and strap connections attached to the transverse strip adjacent its free edge portions, extending upwardly and attached to 75 the upper part of the garment.

2. In combination with a woman's garment of the type that is cut low in the back so as to expose the central part of the back of the wearer, a bust supporter comprising a transverse piece of material extending across the inside of the front portion of the garment above the lower extremity of the cut low portion of the back and terminating at the sides of the garment, thereby leaving the 80 central part of the back of the wearer entirely exposed and avoiding a circumferential restriction around the bust of the wearer, said transverse piece of material being stitched to the front portion of the garment along 85 one edge and having portions of the opposite edge free to fit under the breasts of the wearer, and strap connections attached to the transverse strip adjacent its free edge portions, extending upwardly and attached to 90 the upper part of the garment.

3. In combination with a woman's garment of the type that is cut low in the back

so as to expose the central part of the back of the wearer, a bust supporter comprising a transverse piece of material extending across the inside of the front portion of the garment above the lower extremity of the cut low portion of the back and terminating at the sides of the garment, thereby leaving the central part of the back of the wearer entirely exposed and avoiding a circumferential restriction around the bust of the wearer, said transverse piece of material being shaped along one edge to follow the lower outer curve of the bust and stitched to the front portion of the garment along such edge 110 and at the ends, the opposite edge of said transverse piece being longer to provide a fullness and having free portions for fitting beneath the breasts of the wearer, and shaped to follow the curve of the bust close to the body, and elastic strap connections attached 115

120

125

130

to the free edge portions of the transverse piece adjacent its outer and central portions, those strap connections adjacent each breast having connection with the adjacent shoulder strap of said garment.

⁵ In testimony whereof, I have signed my name to this specification.

JANE C. GIFFORD.
